INCLINED SURFACE BALL GAME

Ferdinand R. Schaefer, Cincinnati, Ohio

Application November 17, 1949, Serial No. 127,873

13 Claims. (Cl. 273—125)

1

My invention relates to amusement devices, more particularly those comprising an inclined surface and a plurality of holes into which balls are rolled.

It is an object of my invention to provide a game of this general type in which two players may participate, competing one against the other.

It is another object of my invention to provide novel means for returning the balls to the respective players, or to a player's opponent, depending on how he rolled the particular ball in question.

Another object of my invention is to provide novel means for indicating the score one has made with the roll of his ball.

Another object of my invention is to provide an amusement device having an inclined surface and a plurality of holes, entrance of a ball into the different holes having a different result, i. e., some holes resulting in the ball being put out of play, others in scores of varying amounts and others in the opponent being given an extra play.

Still another object of my invention is to provide an amusement device which appeals to persons of all ages and which is simple in construction and economical to manufacture.

These, and other objects and advantages of my invention will become apparent to one skilled in the art during the course of the following description with reference being had to the accompanying drawings in which like numerals are employed to designate like parts throughout the same, and in which:

Figure 1 is a top view with parts in section and parts removed, of a device embodying my invention.

Figure 2 is a sectional view taken on the line 2—2 of Figure 1.

Figure 3 is a sectional view taken on the line 3—3 of Figure 2.

Figure 4 is a plan view of a ball retaining member employed with my amusement device.

Figure 5 is a fragmentary sectional view similar to the corresponding part of Figure 2.

Figure 6 is an enlarged sectional view on the line 6—6 of Figure 2.

Figure 7 is a plan view of the scoreboard device of Figure 6.

Figure 8 is a perspective view of a pair of cross-over members, or inclined runways employed with my device.

Figure 9 is a top view with parts broken away and parts in section of a modification of my device.

2

Figure 10 is a section taken on the line 10—10 of Figure 9.

Referring now to Figures 2 and 6, it will be seen that my device may comprise a pair of side members 15 and a base plate 16 fixed thereto in any suitable manner. I have indicated a mortise fit as at 17 in Figure 6. From Figure 2 it will be observed that I have provided the base plate 16 with a stepped ledge as at 18. Ball retaining members 19 are shown in Figures 1 and 2. I have indicated a pair of plane inclined surfaces at 20 and 21 which may, however, as I have shown in Figures 1 and 2, comprise a single member centrally bent in order to provide the surfaces 20 and 21. It should be noted that the surfaces 20 and 21 end as indicated at 22 and 23, respectively, in order to leave room for one to remove any balls which may be resting on the shelf 18 between the end piece 19 and the base 16. The inclined surfaces 20 and 21 may be maintained between the side walls 15 in any suitable manner, it being noted that I have shown them as being maintained by a mortise fit 24 as best seen in Figure 6.

The inclined playing surfaces 20 and 21 are each provided with a plurality of holes 25 and 26 respectively. Located between the rows of holes 25 and 26 is a row of holes 27. A series of blocks 28 separate each of the holes 27 from its adjacent one. Briefly stated, the object of the game is to roll the ball past the row of holes 25 or 26 and into one of the holes 27 located between pairs of the blocks 28. The balls may be rolled by hand, propelled by a conventional shooter, or they may be struck by a golf club or the like.

As is best seen in Figures 5 and 6, I have provided a scoring device comprising a scoreboard 29 having a pair of inclined surfaces 30 and 31 on which the various scores may be printed and a plurality of pendulum members 32 having an indicator 33 at one end thereof and a weighted member 34 at the other end thereof. The scoreboard 29 is mounted above the row of holes 27 by means of a pair of brackets 35 which are fixed to the side walls 15 as is indicated at 36 in Figure 6. Each of the pendulums 32 is pivotally supported on a rod 37 extending between the pair of supporting brackets 35. In order to permit the members 32 to be swung about the rod 37, the scoreboard 29 is provided with slots 38 adapted to receive the upper arms of the pendulums 32. The weighted portion 34 of each of the pendulums 32 is adapted to normally lie just above one of the openings 27. When a ball is rolled up one of the inclined surfaces and into one of the holes

27, in which it will be supported by a member 39 to be more fully described shortly, the weighted end 34 of the pendulum 32 will be pushed out of the way and the indicator 33 tilted in the direction from whence the ball was rolled, thereby indicating that the person who so rolled the ball has scored whatever points are printed on the scoreboard 29 beneath such indicator. I have indicated a game ball at 40 in Figures 5 and 6.

As is best seen in Figure 4, the support 39 just referred to, comprises a rectangular member 39a having a plurality of openings 41. The support 39 is also provided with projections 42, the purpose of which will become apparent shortly. This support 39 may be positioned beneath the row of holes 27 in any conventional manner. I have shown it as being provided with a rod 43 and knob 44 by means of which it may be moved, the rod 43 having a bearing in one of the side walls 15. The other end of the member 39 may be supported by means of screws 45 operating in slots 46 of the member 39 and screwed into the bottom portion of the surfaces 20 and 21. The member 39 is normally positioned so that its solid portions underlie each of the holes 27. Thus when a ball 40 is rolled into one of these holes it will be supported by the member 39. If, however, one of the players actuates the member 39 by pulling the knob 44 the holes 41 can be made to register with the holes 27, in which event the ball 40 will fall from the hole 27 and be returned to one or the other of the players in a manner to be shortly described. The projections 42 are also arranged to underlie certain of the holes 25 and 26 when the member 39 is in its ball supporting position. When the holes 41 are registered with the holes 27, the projections 42 will, of course, be moved from under the holes 25 or 26 and any ball which was thereby supported will also be returned to one of the players.

Extending between the under side of the inclined playing surfaces 20 and 21 and the bottom member 16 are a pair of inclined runways 47 and 48. The exact construction of the runways 47 and 48 does not constitute a limitation of my invention except insofar as I have included such structure in the sub-joined claims, but, I have found that a convenient way in which the surfaces may be formed is to provide a pair of L-shaped members 49 and 51 which may be suitably mitered together, such a structure being shown in perspective in Figure 8. As is best seen in Figure 3, I have provided a shelflike member 52 which is in substantially the same plane as the inclined surface 47 on which it is supported at one end, it being supported at its other end by means of a screw 53 set in the side wall 15. The member 52 is provided with an upturned portion 54 and it is through this portion that the screw 53 extends. A similar shelf 55, which is in substantially the same plane as the inclined surface 48 from which it is supported, extends to the other side wall 15 from which it is supported as at 56. The shelf-like member 55 is provided with an upturned flange 57. In Figure 3 I have superimposed the holes 25, 26 and 27 in dotted lines in order to show the relative position of the inclined surfaces 47 and 48, and the shelflike members 52 and 55, with respect to these holes. It should be noted that any ball 40 which strikes the inclined surface 48 will roll down that surface beneath the shelflike member 52. Any ball which strikes the inclined surface 47 will roll down that surface beneath the shelflike member 55. Those balls, however, which fall

upon the shelflike member 52 will roll against the upstanding portion 54 and over to the inclined surface 47 down which it will proceed. Balls falling upon the shelflike member 55 will roll against the upstanding portion 57, and over to the inclined surface 48 down which it will proceed. The arrangement of these various shelf members and inclined surfaces is best seen in Figures 2, 3 and 6.

10 The operation of my device is as follows:

The players will assume positions at the opposite ends of the device and will be given a plurality of balls. The object of the game is to roll a ball up one of the inclined surfaces 20 or 21, past one of the rows of holes 25 or 26, and into one of the holes 27. The member 39 will be in the position illustrated in Figure 1, in which position balls falling into the holes 27 will be thereby supported. It should be noted that the projections 42 on the member 39 will underlie certain of the holes 25 and 26. Balls which are thrown up either of the surfaces 20 or 21, and which fall in any of those holes 25 or 26 underneath which the members 42 extend, will simply fall into those holes and be supported on the members 42. In this manner it is possible that some of the balls will be put out of play. If desired, those holes under which the projections 42 extend, could be designated as "dud" holes. Others of the holes 25 and 26, however, are not so obstructed and balls which fall into them will result in the opponent getting a free play for such a ball that falls into one of the holes 25, for example, will, by the shelf and surface arrangement 52 and 47, be carried to the opponent opposite the person who originally propelled the ball. Considering Figures 1 and 3, it will be noted that if a ball is rolled up the inclined surface 21 into one of the unobstructed holes 26, it will be transferred by means of the shelf and surface arrangement 55 and 48 to the opponent.

40 As viewed from a player's position at the right of Figure 1, a ball rolling into one of the unobstructed holes 26, at the left side of the surface 21, will simply fall through to the inclined surface 48 and be thereby started on its way towards the opposite end of the game device, passing beneath the shelf 52. Should the ball fall into one of the unobstructed holes 26 toward the right side of the surface 21 the ball would be caught by the shelflike member 55 and be brought over to the inclined surface 48 from which it would also proceed toward the opposite end of the game device. In similar manner, any ball rolled up the surface 20 and into one of the unobstructed holes 25 will be transferred by the inclined surface 47 and shelf 52 to the opposite end of the device. Such an arrangement penalizes the player who is unskillful enough to throw his ball into one of the scoring holes 27 by giving his opponent an extra ball with which to play. As above explained, a ball rolling into one of the obstructed holes 25 or 26 simply results in its being put out of play either by the originator or the opponent. 50 If the player is successful in rolling his ball past the holes 26 or 25 and between the blocks 28 into one of the holes 27, the weighted end 34 of one of the pendulums 32 will be swung out of the way and the score indicated by the member 33. 60 An example of this is best seen in Figures 6 and 7. In these figures it will be observed that one of the balls 40 has been rolled up the inclined surface 21, and into one of the holes 27. The ball 40 which came up the surface 21 has come toward the observer as viewed in Figure 6, and a

score of 50 indicated by one of the members 33, this being best seen in Figure 7. The ball 40 which, by way of example, was rolled up the inclined surface 20, also fell into one of the holes 27 and this happens to be a score of 30 as indicated by the member 33 of Figure 7. This method of scoring prevents any mix-up for it will be observed that the indicator 33 will always be biased toward the direction from which the ball originated. Thus, as seen in Figure 7, the ball originating from the plate 21 fell into a hole 27 which was worth 50 points and this is indicated by the member 33 being positioned adjacent that score near the surface 31 of the scoreboard 29. The ball which came up the inclined surface 20 and fell into a hole worth only 30 points resulted in the indicator 33 being biased toward the flanged portion 30 of the scoreboard 29, which portion 30 is, of course, nearest the person who originated the movement of the ball. When all of the balls have been put out of play by their having been rolled into one of the obstructed holes 25 or 26, or into one of the scoring holes 27, the game is completed and the winner may be determined from the scoreboard 29 and the members 33 operating therewith. The device may be cleared and the balls returned to the ends of the device by movement of the knob 44 and rod 43 to bring the holes 41 into register with the holes 27, this movement at the same time bringing the projections 42 from beneath the holes 25 and 26. The balls that fall through these holes and onto the inclined surfaces 47 and 48 will be propelled along the member 16 to one of the shelves 18, from which they may be taken by the players.

The particular device just described is well suited for manufacture in sizes convenient for use on a card table or the like. In such styles and sizes it is preferable to move the balls either by rolling them with the hand or by shooting them with a conventional shooter.

In Figures 9 and 10 I have illustrated a modification of my invention. In this modification the inclined surfaces 20 and 21 extend to a position flush with the floor or table upon which the device is positioned. This arrangement makes it possible to propel the balls by a golf club, croquet mallet or the like. Those parts of this modification which are similar to those of the first modification are designated with like reference numerals. It will be observed that certain of the holes 25 and 26 are unobstructed while the others are obstructed. In this modification the support for the balls which fall into the holes 27 comprises a pair of frame members 58 joined together by a series of cross bars 59. At one end the frame members 58 are slidably supported in a block 60 supported from one of the side walls 15. At its other end the pair of frame members 58 is supported by the rod 43 and knob 44a which are fixed to one of the cross members 59. A spring 61 serves to normally position the frame members 58 and cross bars 59 in such position that the bars 59 lie directly beneath the holes 27. When the player grasps the knob 44a and slides the members 58 and 59 against the action of the spring 61, the members 59 are moved from beneath the holes 27 and any balls which had been supported by them will fall through and be returned to the various players in a manner to be described shortly. The pendulum arrangement indicated at 32, 33a and 34, is essentially the same as was provided in the first modification described, as is also the scoreboard 29a. When a ball 40 is thrown into one of the holes 27, the

end 33a of the pendulum 32 will be moved in the slot 38 toward that direction from which the ball was thrown. The projections 42, which underlie certain of the holes 25 and 26, are fastened directly to the frame members 58.

In this modification of Figures 9 and 10 I have provided somewhat different means for guiding the balls to the proper players. At 62 I have indicated the provision of a perpendicular plate 10 which is located diagonally across the device between the side walls 15 beneath the inclined surfaces 20 and 21. A substantially triangular shaped, plane member 63 extends between the side walls 15 adjacent the member 62, the angle 15 between any portion of the member 63 and the surface of the base being substantially constant. In similar manner, a substantially triangularly shaped, plane member 64, is positioned between the side walls 15 adjacent the diagonal member 62. One of the side walls 15 is provided with an opening 65 adjacent the lowermost juncture of the triangular member 63 and the diagonal member 62. The other side wall 15 is provided with an opening 66 adjacent the lowermost point of 20 juncture of the triangular member 64 with the diagonal member 62. It will thus be observed that any ball thrown up the inclined surface 21 and which falls into one of the unobstructed holes 26 will then fall onto the angular member 30 25 35 40 45 50 55 60 65 70 75 63, down which it will roll adjacent the diagonal member 62 and out the opening 65 provided in the side wall 15. Such a ball will thus be returned by means of the guide member 67 to the player opposite that who originated movement of that ball. Similarly, a ball which is rolled up the inclined surface 20 and through one of the unobstructed holes 25, will fall onto the triangular member 64 down which it will roll adjacent the diagonal member 62 and out the opening 66 provided in the side wall 15. It will be directed to the player opposite that who initiated that ball's movement by means of the guide rail 68.

It will be noted that any ball supported in the holes 25 and 26 on the supports 42, and those 45 50 55 60 65 70 75 balls supported in the holes 27 on the cross arms 59, will, when the knob 44a is actuated in order to remove these supports fall through to the surface 63 or 64 located directly beneath it. If, at the end of a game, it should turn out that more of the balls are returned to one side of the device than another, it is contemplated that the players will adjust the difference so that each player will begin a game with the same number of balls. In this modification, as in the one first described, the object of the game is to roll a ball up one of the surfaces 20 or 21, past the holes 25 or 26, between the members 28 and into one of the holes 27. When all the holes 27 are filled that person who has scored the most points as indicated by the position of the lever arms 33a, is the winner of the game. In this modification, as in the other, it is possible that a thrown ball may end up in one of the obstructed holes and, therefore, be put out of play by either player or it may go into one of the unobstructed holes and result in the opponent getting an extra play.

It is to be understood that modifications may be made in my invention without departing from the spirit thereof, and it is not my intention to be limited to the specific structure of the embodiments shown except insofar as such structure has been set forth in the subjoined claims. Having thus described my invention, what I claim as new and what is desired to be protected by

1. In a game device comprising a pair of oppositely disposed inclined surfaces each slanting downwardly from a common meeting point, each having a plurality of ball receiving openings adjacent said meeting point, and releasable means to support a ball in one of said openings, guide means positioned below said openings so as to receive a said ball and direct it in a given direction when said releasable means is actuated, said guide means comprising an upright partition located diagonally, centrally of said pair of inclined surfaces in the region of said common meeting point and a second pair of oppositely disposed, inclined surfaces each of which extends downwardly from near one of said first mentioned surfaces to said partition.

2. In a game device according to claim 1, supplementary guide means located adjacent the lowermost point of juncture of each of said second pair of oppositely disposed, inclined surfaces and said partition, said supplementary guide means comprising a ball directing rail.

3. In a game device, a pair of side members, a pair of oppositely disposed, inclined surfaces fixed between said side members and having a plurality of ball receiving openings located in a row substantially at the line of juncture of said surfaces, an upright member located beneath said surfaces and extending diagonally between said side members so as to bisect said row of openings at an angle, a second pair of oppositely disposed, inclined surfaces located beneath said first mentioned pair of surfaces, each of said second pair of surfaces sloping downwardly at a constant angle to said upright member, each of said side members being provided with a ball receiving opening located adjacent the lowermost point of juncture of said upright member with each of said second pair of inclined surfaces, and ball guiding passage means extending from each of said last mentioned openings towards one end of said game device.

4. The game device of claim 3 in which releasable support means adaptable to support balls in said first mentioned openings are provided beneath said first mentioned openings above said second pair of inclined surfaces so that actuation of said support means will result in balls dropping through said first mentioned openings by gravity onto one of said second mentioned pair of inclined surfaces.

5. The device of claim 4 in which each of said first mentioned pair of inclined surfaces is provided with a plurality of additional ball receiving openings, said support means also being adaptable to support balls in certain of said additional openings, blocks separating each of said first mentioned openings from the others, pendulum members supported from said side members and having weighted ends normally positioned above said first mentioned openings between said blocks, and a scoreboard supported from said side members, said scoreboard having slots which receive the upper ends of said pendulum members.

6. In a game device, a pair of oppositely disposed inclined playing surfaces having a plurality of ball receiving openings located in a row and substantially at the juncture of the said two surfaces, releasable means to support a ball in one of said openings, means to direct a said ball in a given direction when said first mentioned means is actuated to release position, means supporting a plurality of normally vertically disposed pendulum members each having a lower weighted end normally positioned just above one of the said

5 openings so as to be struck by a ball rolled towards a said opening, each of said pendulum members being pivotally mounted intermediate its ends, and a slotted member positioned adjacent the upper ends of said pendulum members, said upper ends extending through slots in said slotted member, said slotted member bearing scoring indicia adjacent each slot, whereby a ball rolled into a said opening will engage a pendulum member and cause the upper end of said pendulum member to be moved towards certain of said scoring indicia.

7. A game device according to claim 6 including a pair of side members, said inclined playing surfaces being fixed between said side members, upstanding end pieces located between said side members, each of said oppositely disposed, inclined surfaces extending upwardly from a point removed from the said end piece nearest it, a substantially horizontal base member located beneath said pair of inclined surfaces and extending between said end pieces, said base member having an offset depressed portion adjacent each of said end pieces, and said ball directing means comprising a second pair of oppositely disposed, inclined surfaces located between said first pair of inclined surfaces and said base member, said second pair of surfaces being located side by side in crossed relationship.

8. The device of claim 7 in which each of said second mentioned pair of inclined surfaces is provided with a shelf-like member in substantially the same plane therewith and bridging the other of said second mentioned pair of surfaces.

9. The device of claim 6 including side members between which said inclined playing surfaces are fixed, and in which said plurality of pendulum members are supported from said side members.

10. The device of claim 9 in which said slotted member is supported from said side members.

11. The device of claim 6 in which blocks are provided to separate each of said openings from the other, the weighted end of a said pendulum extending between a pair of said blocks, and in which additional ball receiving openings are provided in each of said inclined playing surfaces, said releasable support means also being adapted to support balls in certain of said additional openings.

12. A game device according to claim 6 in which said ball directing means comprises a second pair of oppositely disposed, inclined surfaces located adjacent each other, each of said last mentioned oppositely disposed, inclined surfaces being provided with a shelf-like member in substantially the same plane therewith and bridging the other of said last mentioned oppositely disposed, inclined surfaces.

13. In a game device, an inclined playing surface having a plurality of ball receiving openings located therein, releasable means to support a ball in one of said openings and guide means positioned below said openings so as to receive a said ball and direct same in a given direction when said first mentioned means is released, said guide means comprising a pair of oppositely disposed, inclined surfaces located adjacent each other, each of said oppositely disposed, inclined surfaces having a shelf-like member fastened thereto and extending in substantially the same plane therewith and bridging the other of said oppositely disposed, inclined surfaces, each of said shelf-like members having an upturned flange along its lower edge, that end of a said shelf-like member which is fastened to its respec-

tive inclined surface being wider than that end of said shelf-like member which lies above the other of said inclined surfaces, whereby any ball falling upon a said shelf-like member will roll against the upturned flange and be guided to its 5 said respective inclined surface.
